UNITED STATES PATENT OFFICE.

CARL MARTIN SIME, OF GRIEBROK, MINNESOTA.

SPEED-REGULATOR.

1,151,907.

Specification of Letters Patent. Patented Aug. 31, 1915.

Application filed March 21, 1914. Serial No. 826,296.

To all whom it may concern:

Be it known that I, CARL MARTIN SIME, a citizen of the United States, residing at Griebrok, in the county of Polk and State of Minnesota, have invented new and useful improvements in Speed-Regulators, of which the following is a specification.

This invention relates to speed regulators for motor vehicles, the object in view being 10 to provide means operating with certainty to cut down the flow of fuel to the engine when the vehicle reaches a certain predetermined speed.

A further object of the invention is to 15 provide means whereby the point at which the regulating device becomes effective may be adjusted to suit the desire of the operator of the vehicle or the traffic regulations.

With the above and other objects in view, 20 the invention consists in the novel construction, combination and arrangement of parts, as will be hereinafter more fully described, illustrated and claimed.

In the accompanying drawings:—Figure 25 1 is a vertical longitudinal section through the casing of the speed regulator, showing the contained mechanism, and showing the relation of the parts to the gasoline feed line pipe of an automobile or other motor vehicle. Fig. 2 is an enlarged detail perspective view of the connection between the governor and cut-off valve of the feed line pipe, showing the means for adjusting the projection thereon.

30 35 In the preferred embodiment of this invention I employ an inclosing box or case 1 of suitable dimensions and preferably of metal, the same being provided with a door 2 to give access to the mechanism contained 40 therein.

Within the box or case 1 I arrange a centrifugal governor comprising a rotary shaft 3 provided with a gear wheel 4 which receives motion from another gear wheel 5 45 on a shaft 6 which may be conveniently driven from one of the axles or wheels of the machine so that the shaft 6 and consequently the shaft 3 revolves at a speed proportionate to the speed at which the vehicle 50 is moving.

The shaft 3 is journaled in suitable bearings within the box or case 1 and is provided with a collar 7 fast thereon to which are connected the adjacent ends of a pair 55 of flexible spring bows 8 carrying weights 9 adjacent to the center thereof and having

their opposite ends connected to a collar 10 which is slideable lengthwise on the shaft 3 as the weights 9 move outwardly and inwardly.

60 11 designates an auxiliary coiled spring which encircles the shaft 3 between the fixed collar 7 and the slideable collar 10.

Connected to the slideable collar 10 and movable therewith is a head or disk 12 65 which in moving lengthwise of the shaft 3 is adapted to come in contact with a projection 13 which is adjustable lengthwise of a connecting rod 14, the projection 13 being in the form of a roller to be engaged by the 70 head 12 and being held at any desired point in the length of the rod 14 by means of a set screw 15.

The rod 14 extends through an opening in the end of the box or case 1 where it is 75 connected to a lever arm 16 on the stem of a cut-off valve 17 which controls the gasoline feed line pipe 18 which extends from the gasoline supply tank to the engine.

In connection with the rod 14 and projection 13 I employ a graduated scale 19 which is shown as graduated in miles per hour the graduations being so arranged that when, for example, the projection 13 is adjusted opposite the graduation designating 20 85 miles per hour, at such point the centrifugal governor will have moved the collar 12 a sufficient distance to come in contact with the projection 13 whereupon the cut-off valve 17 will begin to close thereby cutting 90 down the supply of gasoline and throttling or starving the engine. As soon as the speed of the machine falls below the point set, the cut-off valve 17 starts to open, a 95 suitable opening spring being employed for that purpose.

From the foregoing description it will now be seen that the owner of the car may set the regulator to cut down the supply of gasoline at any predetermined speed of the 100 vehicle and if desired he may set the regulator so that it will not permit the machine to make any appreciable headway thus preventing unauthorized persons from starting and driving the machine. He may also set 105 the regulator in accordance with the traffic regulations so that he may not exceed the speed limit.

While I have shown mechanical means for opening and closing the cut-off valve 17, it 110 will be understood that electrical appliances may be used for the same purpose, such elec-

trical device being thrown into operation by the centrifugal governor when actuated by the mechanism set forth.

What I claim is:—

- 5 The combination with the fuel feed line pipe of a motor vehicle, of a cut-off turn plug valve controlling said pipe, an arm on the stem of said valve, a valve operating rod connected to said arm, a projection adjustable lengthwise of said rod and embodying
- 10 a roller, a centrifugal governor comprising

a rotary disk which acts on said roller, an indicating pointer on said rod, and a graduated scale over which said pointer is movable.

15

In testimony whereof I affix my signature in presence of two witnesses.

CARL MARTIN SIME.
